UNITED STATES PATENT OFFICE

STANLEY S. PIEPGRAS, OF CHICAGO, ILLINOIS

GENERATOR FOR HYDROCARBON BURNERS

Application filed September 16, 1929. Serial No. 392,859.

My invention relates to improvements in generators for hydrocarbon burners and more particularly to generators such as are used in mantle lamps, lanterns, camp stoves 5 and the like.

Generators of the above class commonly comprise a metal tube exposed to the heat of the burner and containing a porous filling material such as asbestos, to retard the flow 10 of liquid fuel under pressure through the tube, thereby allowing for complete gasification of the fuel before it passes through a small outlet orifice into the mixing chamber.

15 The gas thus formed is subjected to the heat while in the generator and becomes "cracked" or decomposed into its lower organic constituents, leaving a deposit of elemental carbon in the generator tube. This 20 deposit cakes in the filling material of the tube, causing stoppage of the generator with the result that a new generator must be substituted as the presence of the filling material prevents convenient cleaning.

25 One object of the present invention is to prolong the service life of hydrocarbon gas generators of the tubular type by providing a novel means within the generator tube which cooperates with the tube to properly 30 restrict the flow of fuel therethrough and which at the same time may be conveniently removed to permit cleaning and then reassembly for further service use.

Another object is to provide a new and improved generator of the above character embodying mechanical means operable automatically during operation of the generator to maintain the carbon in loosened condition thereby preventing clogging of the carbon in 40 the generator tube and prolonging the period over which the generator may be used without cleaning.

Another object is to provide such a generator in which the various parts are held in 45 assembled relation by means which may be economically manufactured and easily and quickly disassembled for purposes of repair or cleaning.

50 Other objects and advantages of the invention will become apparent from the fol-

lowing detailed description taken in connection with the accompanying drawing, in which:

Figure 1 is a fragmentary view in vertical section of a mantle lamp equipped with a 55 generator embodying the features of the present invention.

Fig. 2 is a detailed view showing the generator in vertical central section.

While the invention is susceptible of various modifications and alternative constructions, I have shown and will herein describe in detail the preferred embodiment, but it is to be understood that I do not thereby intend to limit the invention to the specific form 65 disclosed but intend to cover all modifications and alternative constructions falling within the spirit and scope of the invention as expressed in the appended claim.

Referring to the exemplary embodiment 70 of the invention illustrated in the drawing, the numeral 3 represents a thin generator tube adapted to receive fuel oil from a closed tank 4 and to deliver gasified fuel to a mixing chamber 5. In the present instance the tube is flared outwardly at the lower end to form a conical flange 6 which is held seated in a threaded counter bore 7^a in the upper end of the feed pipe 7 by an externally threaded nut 8 which surrounds the tube and is screwed into the counter bore. A valve 9 interposed between the supply tank and the tube 3 is adapted to be regulated by hand to control the flow of fuel under pressure 75 through a tube 10 into the feed pipe.

80 Mounted on a frame structure supported from the fuel tank 4 is a hollow casing 11 constituting the mixing chamber 5 into which air is drawn through an intake tube 12. This casing has two downwardly extending 85 conduits 13 through which the air and gas mixture is supplied to the mantles or burner 14. To provide a heating zone around the tube 3 so that the fuel flowing therethrough will be gasified after the burners are once started in operation, the conduits 13 terminate so as to support the mantles 90 close to the central portion of the tube 3.

95 The upper end of the tube 3 projects loosely through an opening in the casing 11 and 100

is closed by a cap 15 threading into the upper end of the tube and having a pin-hole orifice 16 through which gas is adapted to flow into the mixing chamber at high velocity. A 5 gauze or screen 17 serves to remove the solid particles from the gas before it passes through the orifice 16.

In the preferred form of my improved generator herein illustrated, the tube 3 is 10 made substantially straight and of circular cross section. Disposed within the tube 3 is a member made of non-porous and heat resisting material such as metal and of such size and shape as to confine the flow of liquid fuel 15 to a narrow annular space immediately adjacent the internal surface of the tube 3.

In the embodiment herein illustrated, this 20 member is in the form of a metal rod 19 of a diameter slightly less than the internal diameter of the tube 3 and of a length substantially equal to that of the tube. Thus it will be observed that the rod and tube cooperate to provide a restricted passage-way 20 which is capable of containing only a small volume 25 of liquid or gaseous fuel.

Within the lower end of the tube 3 is positioned a clip 22 formed by bending a piece of resilient wire into a U-shape. When positioned in the tube as shown in Fig. 2, the ends 30 of the clip bear frictionally against the inner wall thereby providing an abutment or support which sustains the weight of the rod 19 and maintains the same in the desired vertical position. Preferably the closed end of the 35 clip 22 extends into the flared end of the tube so as to be readily accessible for manual removal. The clip 22 is, of course, made sufficiently small to permit passage of liquid fuel upwardly from the feed pipe 7 into the tube.

40 In order to prevent caking of the carbon deposit which would obstruct the flow of fuel, means is preferably provided which acts automatically during operation of the generator to maintain said deposit in loosened condition. In the present embodiment, the same 45 means which cooperates with the tube 3 to form the restricted fuel passage 20, that is the rod 19, acts to perform this function. This result is obtained by mounting the rod 50 19 loosely within the tube 3 as above described so as to allow for some degree of lateral and longitudinal movement of the rod as a result of the surging action of the fuel as it enters the lower end of the tube. Vertical 55 movement is provided for by making the rod 19 somewhat shorter than the distance between the abutment formed by the clip 22 and the closed upper end of the tube and allowing the rod to rest upon said abutment.

60 Thus the rod is free to move axially within the generator tube. Lateral movement is provided for by employing a loosely fitting rod and allowing the same to rest freely upon the abutment.

65 The action of the rod in preventing clog-

ging of the generator passage-way is as follows:

The rod 19 tends normally due to gravity to assume its lower position on the abutment formed by the clip 22. During the operation 70 of the generator the upward pressure of the fuel on the lower and surface of the rod tends to overcome the weight of the rod and actually lifts it a slight distance from its lower position. Due to the variable fuel requirements of the generator, the pressure surges of the fuel in the feed pipe, and to the variations in the area on which the fuel pressure is effective as the rod shifts from side to side in the tube 3, the force acting upwardly on 80 the rod varies considerably. When the magnitude of this force is less than the weight of the rod, the latter is allowed to drop. Such vertical movement occurs at frequent intervals during the operation of the generator. 85

I have found that this constant shifting of the rod 19 axially and laterally within the tube 3 tends to break up the carbon particles as they form and maintain them in loosened condition within the restricted generative 90 passage-way. This action effectively keeps the passage-way open for long periods of time thereby making frequent cleaning of the generator unnecessary.

To dismantle the generator tube for replacement, inspection or cleaning, the nut 8 is unscrewed so that the generator tube may be lifted from its operative position. The clip 22 may then be withdrawn and the cap 15 unscrewed to release the rod 19 and the screen 17 so that a small brush or wire may be worked back and forth through the tube 3 to remove any carbon which has been formed therein.

When it is desired to start the generator a 105 lighted match is held adjacent to the tube 3 and due to the fact that the film of oil in the passage-way 20 is so thin, the heat thus provided is sufficient to supply ample gas to 110 operate the burners 14. As soon as the burners 14 have been lighted, the heat supplied thereby serves to vaporize the oil in the generator tube.

In the operation of the generator, the liquid fuel under pressure in the tank flows upwardly through the tube 3 in a thin film of 115 annular cross section and upon entering the heating zone is quickly gasified owing to the fact that the inner tube confines the flow of fuel to the space immediately adjacent the internal surface of the tube. Thus the film of liquid fuel is exposed on one side to the heated tube 3 and on the other side to the outer surface of the rod 19 which is heated by conduction. The result is that the fuel is 120 quickly gasified and continues to flow upwardly at a high velocity owing to the small cross sectional area of the generator passage-way. When flowing at such velocity all particles of the gas move out of the heating zone 125 130

without being entrapped therein or subjected to the high temperature for an interval sufficient to cause a material amount of decomposition or "cracking". The deposit 5 which does form is maintained in loose condition and is continually subjected to a grinding or reducing action by the movements of the rod 19 within the tube.

With the generator thus provided, very 10 little carbon deposit is formed within the generator tube or carried forward through the port 16 so as to cause blocking of the mantles. Since scouring or rubbing action of the rod 19 is continuous during the use of the generator 15 the formation of carbon deposits is substantially eliminated and in case any such deposits are formed they are loosened in very minute particles and further ground by continued action of the rod so that blocking of 20 the pin-hole aperture 16 or the mantles is practically eliminated.

For this reason the generator will operate 25 for a good many more hours before becoming clogged than the generators now in common use. Even when the generator does become clogged, it may be cleaned conveniently and placed back in service. Thus the life of the generator and of the mantles is greatly prolonged thereby materially decreasing the cost 30 of operation of burners of this type. The present generator is also easier to start owing to the fact that liquid fuel to be vaporized is confined in a thin film to the space immediately within the tube 3 where the heat may 35 be applied effectually.

I claim as my invention:

A generator for hydrocarbon burners comprising, in combination, a stationary part 40 providing an upright fuel supply duct, a tube removably supported in vertical position on said part within a heated zone and communicating at its lower end with said duct, a non-porous inner member mounted within said tube so as to define with said tube a restricted fuel passage, and a resilient U-shaped 45 clip having its open end entered into the lower end of the tube and frictionally engaging therewith, the lower end of the clip bearing against said stationary part of the mouth 50 of said duct and the upper end of the clip providing an abutment for supporting said inner member in spaced relation to said duct.

In testimony whereof, I have hereunto affixed my signature.

STANLEY S. PIEPGRAS.
